S. SOKOLOW

PORTABLE ELECTRIC LIGHT

Filed Feb. 1, 1924

UNITED STATES PATENT OFFICE.

SAMUEL SOKOLOW, OF BROOKLYN, NEW YORK, ASSIGNOR TO BRIGHT STAR BATTERY COMPANY, A CORPORATION OF NEW YORK.

PORTABLE ELECTRIC LIGHT.

Application filed February 1, 1924. Serial No. 639,841.

The present invention relates to an improvement in portable electric lights of the kind generally known as "flashlights", wherein an electric battery within a portable casing supplies current to an incandescent bulb carried by the casing. These flashlights are generally provided with a reflector and lens and are so shown herein, although these features form no part of the present invention.

One principal object of the invention is to provide means whereby a more reliable and effective resilient contact is had between the battery terminal and the lamp terminal. Another principal object of the invention is to accomplish the resilient contact between these terminals by means at the forward or lamp end of the casing, instead of at the rear or cover end thereof, as heretofore.

These ends are attained by interposing between the battery and lamp a special element which may be termed a resilient transmitting buffer. This element may take a great variety of forms, without departing from the invention; and it is to be understood that the particular form shown is exhibited by way of example.

The drawing shows an enlarged side elevation partly broken away and partly in longitudinal section of a complete flashlight equipped with my invention.

In the drawing, the outer cylindrical casing is shown at 10, containing a battery 11 of any usual type and closed by a cover 12, preferably screwing onto the rear end. The usual switch is indicated at 13, but as the circuit-closing means form no part of this invention they are not shown in detail.

The usual lamp bulb 14 is carried by a supporting disc 15 which preferably screws into the position shown. The usual reflector 16 is screwed into place on the disc 15 as shown and a shell 17 screws onto the forward end of the device, and preferably carries a lens, not shown.

Most of the features thus far named were known before my present invention, but in the flashlights heretofore used, the battery 11 has rested upon a spring between the bottom thereof and the cover, which spring generally conducts current from the battery to the cover. This spring is used to insure pressure-contact between the "carbon" or central terminal of the battery, shown at 18 herein, against the central or end terminal of the lamp bulb.

My improved construction provides a resilient buffer between the lamp terminal and the battery terminal 18, and the preferred construction of this buffer is shown in section and in somewhat exaggerated 60 proportions in the drawing.

This device as shown comprises a shell 19 containing two independently movable conducting members 20 and 21, mounted in a resilient manner within the shell, in such a 65 manner that pressure and current are transmitted through these members from the battery terminal 18 to the bulb terminal. For this purpose the construction shown in the drawings is preferably used, wherein a 70 spiral spring 22 is mounted between the members 20 and 21, tending to force them apart.

In order to guide the members in their movements and limit the degree of their separation, each member is cupped in the center, each cup being surrounded by a flange normally resting against the fixed insulating discs 23 and 24 respectively. These discs are at opposite ends of the shell 80 19. The cupping of the members 20 and 21, also serves to better hold the ends of the spring 22 in place, so that no soldering or other securing of the spring is necessary.

The form of buffer just described is not 85 herein specifically claimed, as it is claimed in a copending application of mine, filed December 31st, 1924, Serial Number 759023.

It is preferred to shape the forward end of the shell 19, as shown, with a neck 25 90 which screws into a socket carried by the support 15. Into this neck 25 the bulb 14 is preferably screwed.

The batteries used in these flashlights are generally enclosed in an insulating cover, 95 and, as this sometimes slips down a little, it is preferred to insure direct contact between the rear or lower end of the battery and the cover 12 by pressing inward the central 100 part of this cover as shown at 26.

When the parts are assembled as shown in the drawing, the screwing home of the bulb 14 at one end and the cover 12 at the other, causes the bulb to depress the cupped member 20, while the forward terminal 18 of the battery presses in the member 21. The spring 22 which is compressed between these members thus provides a resilient buffer between the lamp and battery, and at the same time insures effective resilient contact be- 110

tween the battery and bulb, permitting the omission of the usual spring within the cover at the rear end of the battery.

Many changes may be made in the structure shown without departing from my invention, which is not limited to the details herein shown and described.

What I claim is—

1. In a portable electric lamp, an outer casing, a removable insulating lamp support at the forward end thereof having a central opening, a metal plate having a threaded neck extending through said open-

ing, a buffer having a threaded neck fitting said first named neck and a lamp bulb adapted to screw into said neck on the buffer. 15

2. Apparatus as in claim 1 in combination with a metal plate on top of the insulating support having a central threaded neck of greater diameter than the opening 20 in said support, and a reflector threaded to fit said neck.

In testimony whereof I have hereto set my hand on this 25th day of January, 1924.

SAMUEL SOKOLOW.
